[57] CLAIM

The ornamental design for a computer central processing unit cabinet, substantially as shown and described.

DESCRIPTION

FIG. 1 is a front and right side perspective view of a computer central processing unit cabinet showing my new design;

FIG. 2 is a right side elevational view with the left side elevational view and a mirror image thereof;

FIG. 3 is a top plan view;

FIG. 4 is a back elevational view;

FIG. 5 is a bottom plan view; and

FIG. 6 is a front elevational view on an enlarged scale.
